FIG. 1 is a front, top, and side perspective view of a pool lighting adapter plate for plaster showing a new design;
FIG. 2 is a rear, top, and side perspective view thereof;
FIG. 3 is a top view thereof;
FIG. 4 is a side view thereof;
FIG. 5 is a bottom view thereof;

FIG. 6 is a front, bottom, and side perspective view thereof;
FIG. 7 is a rear, bottom, and side perspective view of the bottom thereof; and,

FIG. 8 is a sectional view thereof taken along line **8-8** in FIG. 3.

The broken line shown in FIG. 3 represents the viewing plane in which the sectional view of FIG. 8 is taken from and forms no part of the claimed design.
